UNITED STATES PATENT OFFICE.

JOHN H. PARSONS, OF PHILADELPHIA, PENNSYLVANIA, ASSIGNOR TO PARSONS ENGINEERING COMPANY, OF WILMINGTON, DELAWARE, A CORPORATION OF DELAWARE.

FURNACE.

1,092,851.

Specification of Letters Patent. Patented Apr. 14, 1914.

Application filed October 29, 1907, Serial No. 399,702. Renewed August 16, 1913. Serial No. 785,126.

To all whom it may concern:

Be it known that I, JOHN H. PARSONS, a citizen of the United States, residing at Philadelphia, in the county of Philadelphia and State of Pennsylvania, have invented 5 certain new and useful Improvements in Furnaces, of which the following is a specification, reference being had therein to the accompanying drawing.

- 10 This invention relates to improvements in furnaces, and has for its object the provision of means facilitating the combustion of fuel with the resultant saving in the fuel and increased efficiency of the furnace.
- 15 The invention comprehends an attachment which may be readily put in place or removed from the fire-box of a furnace without the necessity of connecting or fastening instrumentalities, formed to inject air, 20 steam or both into the products arising from the fuel bed to insure complete combustion of said products.

The invention also embraces in a device of this general character, a specially formed 25 injecting nozzle whereby to emit over the fuel bed, the said air, steam or both in the proper form and at the proper place or places to insure the perfect combustion sought, without otherwise impairing the efficiency of the furnace, as for instance, impeding the required draft for the burning 30 bed of fuel.

The invention also embraces a novel arrangement of the attachment within the fire 35 box, and incidentally the special formation of the attachment enabling such arrangement, whereby the air, etc., passing through the attachment will be readily heated to the desired degree,—preferably to the point of 40 ignition when commingled with the gaseous products arising from the fuel,—before its discharge from the nozzle.

The invention further includes the special 45 formation of the attachment whereby the same may be interchangeable with the grate bars of the furnace.

The invention still further includes a 50 novel coupling means whereby a steam or other jet nozzle may be connected to the receiving or inlet end of the attachment to create a forced suction or draft through the attachment in such instances as this may be found necessary or expedient.

All of the foregoing characteristics of the

present invention, and also other novel details in the construction and arrangement of parts will be fully understood from the detailed description hereinafter contained when read in connection with the accompanying drawings forming part hereof and 60 wherein one convenient embodiment of the invention is illustrated.

In the drawings: Figure 1 is a vertical longitudinal sectional view, parts being broken away, through a steam boiler furnace of 65 ordinary type having the improvements applied to the fire-box thereof, Fig. 2 is a vertical transverse sectional view on the line α — α of Fig. 1 looking forwardly of the fire-box, Fig. 3 is a perspective view of one of 70 the attachments removed from the fire-box. Fig. 4 is a transverse sectional view through Fig. 3, and Fig. 5 is a view similar to Fig. 1 showing the invention applied to a steam locomotive. 75

Referring more specifically to the drawings wherein like reference characters refer to corresponding parts in the several views, A designates the fire-box of a steam boiler furnace, B being the bridge wall at the rear 80 of the fire-box, C the combustion chamber or arm in rear of the fuel bed and above the bridge wall, D the water tubes, E the top of the fire box, F the grate bars thereof, and G the furnace charge openings. Running transversely across the fire chamber in 85 a plane near the bottom of the openings G is a horizontal ledge H, and at the forward upper edge of the bridge wall B is a corresponding ledge I, while intermediate the 90 two and midway the fire chamber is a supporting bar J, said ledges and bar co-operating to support the two series of grate bars F resting thereon, the ends of the grate bars being, as usual, removably inserted in 95 open-topped grooves or pockets f' in the ledges H and I and intermediate bar J.

Now referring for the present especially to Fig. 3 wherein one of the attachments made in keeping with the invention is 100 clearly shown, it will be noted that said attachment comprises an elongated substantially horizontally disposed pipe K, the upper surface thereof being rounded transversely, while the under surface k of which 105 is flat. One end of this pipe K is formed into an elbow directed upwardly substantially at a right angle, as at L, and the

other end is similarly formed into an elbow, directed downwardly and forwardly at an acute angle, as at M. Formed on the last mentioned elbow M is an outwardly 5 projecting lug *i*, a corresponding lug *h* projecting outwardly from the elbow L. The pipe just described is preferably formed of iron. Removably placed upon the upper open end of the elbow L is an injecting 10 nozzle N, preferably formed of fire brick or iron having a shoulder *n* at its lower end to seat upon the surface of the end of the elbow L, and a collar or flange *n'* depending over the outside of said elbow end to 15 confine the nozzle against bodily movement laterally. The outlet or emitting end of the nozzle, is represented at O and is formed by flattening and turning the end of the nozzle inwardly, and inclining said end inwardly as best seen in Fig. 1. When the 20 attachment as just defined, is placed in the fire-box of a furnace, it is simply necessary to remove one or more of the grate bars F and insert the attachment in lieu thereof, 25 the flat under surface *h* permitting the same to lie flat upon the transverse bar J and the lugs *i* and *h* respectively, seating upon the ledges I and H, as is obvious. No other means is necessary to secure the attachment 30 in place nor to prevent disarrangement thereof when properly positioned in the fire-box. I conveniently arrange one of these attachments near each side wall of the fire-box and whereby the elbow M will project down into the ash-pit *m* to receive air 35 therefrom, said air being heated to a high degree by its passage through the elongated pipe K embedded in the burning fuel bed, and the nozzles N being arranged whereby 40 the heated air emitted therefrom will be in the form of a sheet overhanging the fuel bed and moving in a plane rearwardly into the combustion area C and just above or away from impact with the bridge wall B, 45 whereby the products arising from the fuel must of necessity commingle with the highly heated air and ignite when so commingled to secure the perfect combustion sought. The inward inclination or beveling 50 of the nozzles directs the sheets of air from the opposite corners of the fire-box toward each other to unite into a conjoint or single sheet at the rear of the bed of fuel, and to some extent impact to spray in the combustion 55 area to further the commingling process.

I have found that the arrangement set forth herein results in a considerable saving of fuel, more intense heat, the preservation and at times increasing of draft through the 60 fuel, greater steaming efficiency of the boiler, and less damage to the boiler from fluctuations of temperature in the furnace, also decreased labor on the part of the attendants.

65. In some instances, as for example, where

the draft through the furnace stack is not sufficient to create the forced current of air through the pipe K and its nozzle N, it is desirable to couple therewith a steam, compressed air or equivalent jet nozzle. Such 70 a nozzle is represented at Q at the end of a pipe R leading from any suitable source of supply and is attached to the open end of the elbow M through the medium of a coupling S, the latter having an annular flange 75 or collar at one end formed to encompass said end of the elbow and be clamped thereto by a bolt T, an open ended body portion U permitting the air to be sucked there-through, and a ring V arranged centrally of 80 said open end for the reception of the jet nozzle Q, a binding screw W being also employed in this instance and passed through the ring to clamp the nozzle in proper adjusted position. As a means for 85 securing the attachments when used in series at proper predetermined distances apart, I employ a tie-rod Z extending across the ash-pit and engaging ears *z* on the couplings S.

In Fig. 5, the invention is shown as used in connection with a steam locomotive, the inlet ends M' of the pipes K' being extended outwardly through the front wall of the fire-box to be exposed to the atmosphere 95 whereby the travel of the engine will force the air through the pipes and nozzles N'. The jet nozzle Q' in this embodiment of the invention is in communication with a valved connection R' communicating with the 100 steam dome of the locomotive. In this particular structure it will also be noted that the attachment is readily applied to such fire boxes as employ transverse grate bars F', the flat bottoms *h'* of the pipes K' simply resting upon the upper surfaces of said 105 transverse grate bars.

In both of the embodiments of the invention described above, the nozzles N and N' being of flattened formation whereby to 110 more readily form the sheets of air, the upper and lower walls thereof come relatively close together, and to prevent impairment thereof,—as for instance by such walls collapsing or buckling together under intense 115 heat,—they are reinforced by a centrally disposed partition or diaphragm 2 bridging the space therebetween and extending not only through the flat end of the nozzle but also to a substantial extent down into the 120 cylindrical stem thereof,—note the dotted line in Fig. 3. These nozzles are conveniently formed of fire-brick or similar substance capable of withstanding the heat.

Under some conditions of use it may be 125 found desirable to securely fasten the attachment in place, as by connecting the same to the cross-bar J, (Fig. 1) or one of the grate bars F' (Fig. 5), and for this purpose I cast a pair of apertured lugs 3, 3, on the 130

bottom of the horizontal pipe spaced apart to receive the bar and be bolted thereto beneath the same as at 4.

Where I refer to the attachment as being "self-supporting" it is with the intention of defining a structure which may simply be placed in position within the fire chamber, and being capable of remaining in such placed position without the necessity of 10 curing devices or any special formation of or additions to the ordinary fire-box.

Having thus described the invention what is claimed is:—

1. In combination with the fire box of a furnace and its grate structure, of an attachment for injecting air into the fire chamber above the fuel comprising an elongated imperforate heater adapted to occupy a position near the plane of the grate but extending upwardly above said plane so as to be embedded in the fuel, an upwardly conducting portion at the forward end of the heater terminating in a flat nozzle adapted to discharge air in sheet formation rearwardly over the fuel, and an intake portion leading to the other end of the heater, said heater being provided with a broad flat base portion adapted to engage the grate structure to support the attachment against lateral tilting movement and the upper portion of the heater being rounded to expose its sides to the fuel, substantially as described.

2. In combination with the fire box of a furnace and its grate structure, of an attachment for injecting air into the fire chamber above the fuel comprising an elongated

imperforate heater adapted to occupy a position near the plane of the grate but extending upwardly above said plane so as to be embedded in the fuel, an upwardly conducting portion at the forward end of the heater terminating in a flat nozzle adapted to discharge air in sheet formation rearwardly over the fuel, and an intake portion leading to the other end of the heater, said heater being provided with depending lugs adapted to engage on opposite sides of the grate structure to maintain the attachment against displacement.

3. In combination with the fire box of a furnace and its grate structure, of an attachment for injecting air into the fire chamber above the fuel comprising an elongated heater adapted to occupy a position near the plane of the grate but extending upwardly above said plane so as to be embedded in the fuel, an upwardly conducting portion at the forward end of the heater terminating in a flat nozzle adapted to discharge air in sheet formation rearwardly over the fuel, and an intake portion offset in a downward direction from the heater to pass through the grate structure into the ash pit, said depending portion passing between the grate bars to prevent lateral movement of the attachment.

In testimony whereof I affix my signature in presence of two witnesses.

JOHN H. PARSONS.
